ABSTRACT OF THE DISCLOSURE

Liquid shaving compositions comprising liquid, non-ionic surfactant and having an HLB from 1 to 9 and a viscosity from 0.1 to 50 stokes at 25° C. Method of shaving which comprises wetting the portion of the skin to be shaved, applying a liquid shaving composition of this invention onto the cutting edge of a razor to provide a thin layer thereon, and advancing the cutting edge of the razor over the dampened surface of the skin to sever the hair fibers.

This invention relates to new and improved methods of shaving and to shaving compositions for use with razor and blade in shaving face, legs, underarms, or other portions of the body from which it may be desirable to remove hair.

The term "HLB" as used throughout the specification and appended claims represents the hydrophile-lipophile balance of a surfactant as determined by the method set forth in the Journal of the Society of Cosmetic Chemists, vol. 1, pages 311-326 (1949).

It is an object of this invention to provide shaving compositions which have improved shaving properties. It is another object of this invention to provide shaving compositions which have superior lubricating properties to minimize razor drag and the resultant irritation which can be caused by this means. It is another object of this invention to provide a shaving composition which will deposit a protective layer on the area shaved to enhance the protective action of skin oils. It is another object of this invention to provide a shaving composition which acts to protect the razor blade between uses by providing a coating thereon. It is another object of this invention to provide a shaving composition which may be applied directly to the edge of the cutting blade. It is another object of this invention to provide shaving compositions which give a close, comfortable, rapid, convenient shave. It is another object of this invention to provide an improved method of shaving. These and other objects of the present invention are accomplished by the shaving compositions and method of shaving therewith set forth in detail in the following description and appended claims.

The liquid shaving compositions of this invention comprise liquid, nonionic surfactant and have an HLB value from 1 to 9 and a viscosity from 0.1 to 50 stokes at 25° C.

The liquid nonionic surfactant may be (1) any liquid, nonionic surfactant which has an HLB value from 1 to 9 and a viscosity from 0.1 to 50 stokes at 25° C. or (2) a mixture of one or more liquid, nonionic surfactant with one or more other liquid, nonionic surfactant wherein the particular surfactants and amounts of each surfactant are chosen so that the resulting mixture of surfactants has an HLB value from 1 to 9 and a viscosity from 0.1 to 50 stokes at 25° C. When two or more surfactants are combined or blended, the HLB values are additive in behavior. Thus, if four parts of a surfactant having an HLB value of 5 is blended with 1 part of a surfactant having an HLB value of 15, the resulting blend will have an HLB value of four-fifths of 5 plus one-fifth of 15, that is four plus three or 7. The amount of liquid, nonionic surfactant

2

present in the shaving composition may vary from 40% to 100% by weight.

Illustrative examples of nonionic surfactants which may be used in the liquid shaving compositions of this invention include propylene glycol esters of fatty acids having from 12 to 24 carbon atoms, for example, propylene glycol monooleate and propylene glycol monolaurate; esters of hexitols and fatty acids having from 12 to 24 carbon atoms, for example, sorbitan monolaurate, sorbitan monooleate, sorbitan trioleate, and sorbitan sesquioleate; esters of glycerine and fatty acids having from 12 to 24 carbon atoms, for example, glycerol monooleate, glycerol dioleate, and glycerol trioleate; polyoxyethylene ethers of partial hexitan esters of fatty acids having from 12 to 24 carbon atoms, for example,

polyoxyethylene(20)sorbitan monolaurate, polyoxyethylene(4)sorbitan monolaurate, polyoxyethylene(20)sorbitan monopalmitate, polyoxyethylene(20)sorbitan monostearate, polyoxyethylene(20)sorbitan monooleate, polyoxyethylene(5)sorbitan monooleate, and polyoxyethylene(20)sorbitan trioleate; polyoxyethylene ethers of fatty alcohols having from 12 to 24 carbon atoms, for example,

polyoxyethylene(4)lauryl ether, polyoxyethylene(10)oleyl ether, polyoxyethylene(2)oleyl ether, polyoxyethylene(12)tridecyl ether, polyoxyethylene(4)isohexadecyl ether, polyoxyethylene(15)isohexadecyl ether, and polyoxyethylene(6)isohexadecyl ether;

polyoxyethylene esters of fatty acids having from 12 to 24 carbon atoms, for example, polyoxyethylene(2)laurate and polyoxyethylene(8)laurate; and fatty acid esters of hexitols, for example, polyoxyethylene(40)sorbitol septaoleate. The monoesters referred to above also include the commercially available monoesters which may contain minor amounts of higher esters. For example, the term "glycerol monooleate," as used throughout the specification and appended claims, includes the commercially available glycerol monooleates which may contain minor amounts of glycerol dioleate and minor amounts of glycerol trioleate.

The preferred liquid nonionic surfactant is a mixture of a glycerol mono ester of a fatty acid having from 10 to 24 carbon atoms and a polyoxyethylene ether of a partial sorbitan ester of fatty acid, said ether containing from 2 to 25 oxyethylene groups and said fatty acid having from 10 to 24 carbon atoms. Illustrative examples of fatty acids having from 10 to 24 carbon atoms include capric acid, lauric acid, lauroleic acid, myristic acid, myristoleic acid, pentadecanoic acid, palmitic acid, palmitoleic acid, stearic acid, oleic acid, margaric acid, linoleic acid, linolenic acid, ricinoleic acid, dihydroxy-stearic acid, arachidic acid, behenic acid, and lignoceric acid. The preferred glycerol mono ester is glycerol monooleate, and the preferred polyoxyethylene ether is polyoxyethylene(20)sorbitan monolaurate.

While the only essential ingredient of the liquid shaving compositions of this invention is liquid nonionic surfactant, the shaving compositions of this invention may contain up to 15% by weight water and up to 25% by weight of an alcohol selected from the group consisting of propylene glycol, ethanol, and isopropanol. The water and alcohol improve the shaving properties and lower the freezing point of the shaving compositions.

The shaving compositions of this invention may also contain various additaments such as hexachlorophene, menthol, perfumes, lanolin, mineral oil, colors, petrolatum, carboxymethylcellulose, emulsifiers, vitamins, hexadecyl alcohol, isopropyl myristate, allantoin, and carboxy

vinyl polymers. The amount of additaments present in the shaving composition will depend upon the particular additaments used. For example, hexachlorophene and vitamins are employed in very small amounts, such as less than 1% by weight, whereas the amount of mineral oil used may be 50% by weight.

following examples of liquid shaving compositions are given. These examples are set forth solely for the purpose of illustration and any specific enumeration of details contained therein should not be interpreted as expressing limitations of this invention. All parts and percentages are by weight, unless otherwise stated.

Ingredient	HLB ¹	Viscosity ²	Example number, percent						
			1	2	3	4	5	6	7
Glycerol monooleate	2.8	77.8							87.4
Sorbitan monolaurate	8.6	30	100						
Sorbitan monooleate	4.3	19		100					
Sorbitan trioleate	1.8	2.7			100				
Sorbitan sesquioleate	3.7	15				100			95
Polyoxyethylene(2)oleyl ether	4.9	0.3				100			95
Polyoxyethylene(20)sorbitan monolaurate	16.7	3.3	6.6				6.6		
Water				6				6	
Propylene glycol				9.6					
Spice perfume							5		5

¹ HLB of ingredient. ² Viscosity of ingredient at 25° C. in stokes.

A preferred group of liquid shaving assisting compositions of this invention is those which comprise a mixture of the following ingredients in the following amounts:

(a) 60% to 97% by weight of liquid nonionic surfactant having an HLB value from 1 to 9 and a viscosity from 0.3 to 30 stokes at 25° C.;

(b) 2% to 25% by weight of an alcohol selected from the group consisting of propylene glycol, ethanol, and isopropanol; and

(c) 1% to 15% by weight of water.

Within the above preferred group of liquid shaving

20 Shaving tests were conducted on each of the foregoing shaving compositions by each member of a ten man shaving panel. Each shave was conducted by wetting the face with water, applying the shaving composition to the cutting edge of a razor, and advancing the cutting edge of the razor over the dampened surface of the face. The shaving composition gave a close, comfortable, convenient, rapid shave.

Additional formulations of shaving compositions which give close, comfortable, convenient, rapid shaves are shown in Examples 10-16.

Ingredient	HLB ¹	Vis- cosity ²	Example number, percent						
			10	11	12	13	14	15	16
Glycerol monooleate	2.8	73.9		90			60	62.2	38.9
Sorbitan monolaurate	8.6	30	10				12		
Sorbitan monooleate	4.3	19	55						
Sorbitan trioleate	1.8	2.7			70				
Polyoxyethylene(2)oleyl ether	4.9	0.3	10				10		
Polyoxyethylene(20)sorbitol monolaurate	16.7	3.3	6.3					5.3	3.3
Polyoxyethylene(20)sorbitol monopalmitate	15.6	5.0			5				
Polyoxyethylene(20)sorbitol monostearate	14.9	5.5				6			
Polyoxyethylene(20)sorbitol monooleate	15.0	4.2				2

¹ HLB of ingredient.

² Viscosity of ingredient at 25° C. in stokes.

assisting compositions of this invention, there may be mentioned those compositions which comprise a mixture of the following ingredients in the following amounts:

(a') 60% to 90% by weight of a glycerol mono ester of a fatty acid having from 10 to 24 carbon atoms;

(a'') 20% to 2% by weight of a polyoxyethylene ether of an ester of sorbitan and fatty acid, said ether containing from 2 to 25 oxyethylene groups and said fatty acid containing from 10 to 24 carbon atoms;

(b) 2% to 25% by weight of an alcohol selected from the group consisting of propylene glycol, ethanol, and isopropanol; and

(c) 1% to 15% by weight of water.

A still more preferred group of liquid shaving assisting compositions of this invention is those which comprise:

(a') 76% to 80% by weight of glycerol monooleate;

(a'') 6% to 9% by weight of polyoxyethylene(20)sorbitan monolaurate;

(b) 8% to 11% by weight of propylene glycol; and

(c) 5% to 8% by weight of water.

The liquid shaving assisting compositions of this invention may be prepared in any desired manner such as by merely mixing the ingredients together and stirring to form a homogeneous mixture.

In order that those skilled in the art may better understand how the present invention may be practiced, the

50 The liquid shaving compositions of this invention may be used in the same way as shaving compositions known prior to this invention. For example, the liquid shaving compositions of this invention may be applied to the skin, alone or in conjunction with conventional shaving compositions, by patting or rubbing on with the hand or fingers, or by rolling on with a mechanical roller, or by spraying on from a pressurized container. It has been found, however, that a greatly improved shaving operation can be achieved by wetting the portion of the skin to be shaved with water, applying a liquid shaving assisting composition of this invention onto the cutting edge of a razor blade to provide a thin layer thereon, and advancing the cutting edge of the razor blade over the dampened surface of the skin to sever the hair fibers. The preferred method of shaving comprises washing the 55 face with soap and water, removing the soap but leaving the face wet, applying conventional shaving cream or lather to the face, applying a liquid shaving composition of this invention onto the cutting edge of a razor blade and onto the head of the razor to provide a thin layer thereon, and advancing the cutting edge of the razor blade over the face to sever the hair fibers.

60 Although this invention has been described with reference to specific chemical materials, it will be apparent that still other different and equivalent chemical materials may be substituted for those described, all within the 65

spirit and scope of this invention as defined in the appended claims.

What is claimed as new and desired to be protected by Letters Patent is:

1. A liquid shaving assisting composition which has an HLB value from 1 to 9 and a viscosity from 0.1 to 50 stokes at 25° C. and which comprises a mixture of 60% to 97% by weight of liquid, nonionic surfactant having an HLB value from 1 to 9 and a viscosity from 0.1 to 50 stokes at 25° C.; 2% to 25% by weight of an alcohol selected from the group consisting of propylene glycol, ethanol, and isopropanol; and 1% to 15% by weight of water.

2. A liquid shaving assisting composition of claim 1 wherein said nonionic surfactant is a blend of nonionic surfactants.

3. A liquid shaving assisting composition of claim 2 which comprises a mixture of 90% to 60% by weight of a glycerol mono ester of a fatty acid having from 10 to 24 carbon atoms and 20% to 2% by weight of a polyoxyethylene ether of a sorbitan fatty acid partial ester, said ether containing from 2 to 25 oxyethylene groups and said last mentioned fatty acid having from 10 to 24 carbon atoms.

4. A liquid shaving assisting composition of claim 3 which comprises a mixture of 76% to 80% by weight of glycerol monooleate, 6% to 9% by weight of polyoxyethylene(20)sorbitan monolaurate, 8% to 11% by weight of propylene glycol, and 5% to 8% by weight of water.

5. A method of shaving which comprises wetting the portion of the skin to be shaved with water, applying liquid nonionic surfactant having an HLB value from 1 to 9 and a viscosity from 0.1 to 50 stokes at 25° C. onto the cutting edge of a razor to provide a thin layer thereon, and advancing the cutting edge of the razor over the dampened surface of the skin to sever the hair fibers.

6. A method of shaving which comprises wetting the portion of the skin to be shaved with water, applying the liquid shaving assisting composition of claim 1 onto the cutting edge of a razor to provide a thin layer thereon, and advancing the cutting edge of the razor over the dampened surface of the skin to sever the hair fibers.

7. A method of shaving which comprises wetting the portion of the skin to be shaved with water, applying the liquid shaving assisting composition of claim 2 onto the cutting edge of a razor to provide a thin layer thereon, and advancing the cutting edge of the razor over the dampened surface of the skin to sever the hair fibers.

8. A method of shaving which comprises wetting the portion of the skin to be shaved with water, applying the liquid shaving assisting composition of claim 3 onto the cutting edge of a razor to provide a thin layer thereon, and advancing the cutting edge of the razor over the dampened surface of the skin to sever the hair fibers.

9. A method of shaving which comprises wetting the portion of the skin to be shaved with water, applying the liquid shaving assisting composition of claim 4 onto the cutting edge of a razor to provide a thin layer thereon, and advancing the cutting edge of the razor over the dampened surface of the skin to sever the hair fibers.

10. A method of shaving which comprises washing the face with soap and water, removing the soap but leaving the face wet, applying shaving lather to the face, applying liquid nonionic surfactant having an HLB value from 1 to 9 and a viscosity from 0.1 to 50 stokes at 25° C. onto the cutting edge of a razor to provide a thin layer thereon, and advancing the cutting edge of the razor over the face to sever the hair fibers.

11. A liquid shaving assisting composition of claim 1 wherein said non-ionic surfactant is selected from the group consisting of propylene glycol esters of fatty acids having from 12 to 24 carbon atoms, esters of hexitans and fatty acids having from 12 to 24 carbon atoms, esters of glycerine and fatty acids having from 12 to 24 carbon atoms, polyoxyethylene ethers of partial esters of hexitan and fatty acids having from 12 to 24 carbon atoms, polyoxyethylene ethers of fatty alcohols having from 12 to 24 carbon atoms, polyoxyethylene esters of fatty acids having from 12 to 24 carbon atoms, fatty acid esters of polyoxyethylene ethers of hexitols, and mixtures thereof.
